UNITED STATES PATENT OFFICE.

ARTHUR L. HALLIDAY, OF YONKERS, NEW YORK, ASSIGNOR TO THE BIGELOW CARPET COMPANY, OF CLINTON, MASSACHUSETTS.

DESIGN FOR A CARPET.

SPECIFICATION forming part of Design No. 12,425, dated August 23, 1881.

Application filed July 14, 1881. Term of patent 3½ years.

To all whom it may concern:

Be it known that I, ARTHUR L. HALLIDAY, of Yonkers, in the county of Westchester and State of New York, have invented a new and original Design for Carpets, of which the following is specification.

This invention relates to a new and original design for carpets and similar fabrics; and it consists in the novel grouping and configuration of figures hereinafter more fully described.

The accompanying photograph illustrates a face view of a carpet having my new design.

A is a group composed of an open rose, *a*, with leaves and branches bearing leaves and flowers projecting around it. The group A also contains the figure *b*, composed of thick leafy foliage, with flowers scattered through it at intervals, and with projecting leafy branches and sprays, and this figure *b* is closely joined to the figure *a* by thick leafy foliage. The whole group A is apparently supported on one side by the L-shaped trellis-work *c* and on another side by the rectangular trellis-work *d*.

The figure B consists of an open rose in the center, surrounded by leaves, leafy branches, and sprays, and having at one side the trellis-work *c*, connecting it with the group A.

The figure C consists of a center of circular flowers and an open rose surrounded by leafy branches and sprays, and having projecting from it the mossy spray *g*, and connected by the rectangular trellis-work *d* with the group A.

The figure *e* consists of a flower and sprays somewhat resembling a crab. The figure *f* consists of a flower center surrounded by slender mossy sprays. These two figures *e* and *f* appear at frequent intervals in the spaces between the groups and figures heretofore described.

I claim—

1. The design for carpets, consisting of group A, containing figures *a* and *b*, substantially as shown.
2. The design for carpets, consisting of the figure B, substantially as shown.
3. The design for carpets, consisting of the figure C, substantially as shown.
4. The design for carpets, consisting of the figures C, *d*, and *g*, substantially as shown.
5. The design for carpets, consisting of the group A and figures B and *c*, substantially as shown.
6. The design for carpets, consisting of the figure *e*, substantially as shown.
7. The design for carpets, consisting of the group A and figures C, *d*, and *g*, substantially as shown.
8. The design for carpets, consisting of group A, containing figures *a* and *b*, figures B, *c*, *d*, *e*, and *f*, substantially as shown.

ARTHUR L. HALLIDAY.
